WATER COOLED VACUUM TUBE

Ilia E. Mouromtseff, Wilkinsburg, Pa., and Gregory V. Rylsky, New York, N. Y., assignors to Westinghouse Electric and Manufacturing Company, a corporation of Pennsylvania

Application February 6, 1932, Serial No. 591,338

7 Claims. (Cl. 250—27.5)

Our invention relates to vacuum tubes and particularly to transmitter tubes having water-cooling jackets.

In high-power transmitter tubes, the anode usually forms part of the vacuum tube envelope and is surrounded by a water-cooling jacket, a flow of water being maintained between the anode and the jacket. When this structure is employed, a rapid flow of water is desired in order to dissipate the heat, and, in order that the water may be passed through the cooling jacket at a high velocity without utilizing too great a volume of water, the spacing between the anode and the inner surface of the cooling jacket is made very small.

An object of our invention is to provide means for so directing the flow of water in the above-mentioned small spacing that more efficient cooling will be obtained.

A further object of our invention is to provide a structure in which the close fitting tubular casting around the anode shall always be spaced from the anode a certain amount.

In practicing our invention we form longitudinal ribs on the anode and surround it with a metallic tube which is split in order that it may be slipped over a seal in the envelope. The split tube is supported directly from the anode by means of metallic supports or feet. A solid tube, which forms a portion of a water-tight chamber, is closely fitted over the split tube.

The longitudinal ribs on the anode are provided for the main purpose of so directing the flow of water that maximum cooling of the anode is obtained.

Other features and advantages of our invention will appear from the following description taken in connection with the accompanying drawing, in which:

Figure 1 is a longitudinal section of a portion of a vacuum tube envelope and of a cooling jacket constructed in accordance with our invention.

Fig. 2 is an enlarged view taken on the line II—II of Fig. 1, and

Fig. 3 is an enlarged view in elevation of the split tube.

Referring to Fig. 1, the vacuum tube comprises an envelope which consists of a metallic anode 11 having a glass blank 12 sealed to it at one end and a glass blank 13 sealed to the other end. The filament and control electrodes are not shown in Fig. 1 for the sake of clearness but are illustrated in Fig. 2. The complete tube, with the exception of our improved form of cooling jacket, is shown in application Serial No. 344,772, filed March 6,

1929, now Patent No. 1,944,190 issued January 23, 1934, in the name of Ilia E. Mouromtseff, and application Serial No. 358,608, filed April 27, 1929, now Patent No. 1,973,094 issued September 11, 1934, in the name of Ilia E. Mouromtseff and Gregory V. Rylsky, both applications being assigned to the Westinghouse Electric & Manufacturing Company. The cooling jacket disclosed in these figures constitutes an improvement on the cooling jacket disclosed in our copending application, Serial No. 227,425, filed October 20, 1927 for Vacuum tubes, now Patent No. 1,971,988 issued August 28, 1934. The cooling jacket disclosed in these figures constitutes an improvement on the cooling jacket disclosed in our copending application, Serial No. 227,425, filed October 20, 1927 for Vacuum tubes.

In accordance with our invention the anode 11 is provided with longitudinal ribs 10 and with a close fitting cooling jacket 14. This structure causes the water to flow in substantially straight lines along the longitudinal axis of the tube. The ribs 10 make it impossible for the jacket 14 to come into contact with the anode 11, in which case the cooling liquid would fail to reach a portion of the anode.

The cooling jacket cylinder 14, which is split to make it flexible, is slipped over the anode 11 and is supported directly from the anode 11 by means of metallic feet 15 bolted, or otherwise secured, to the cylinder 14. The split cylinder 14 is held in position by wrapping wire 16 around the anode 11 and feet 15.

The manner in which the cylinder 14 is split will be seen by referring to Fig. 3. On the under side of the cylinder, a saw cut 17 extends the entire length of the cylinder. On the upper side of the cylinder 14, two saw cuts 18 and 19 extend for only a portion of its length. In this manner, the cylinder is made flexible enough, so that its diameter may be increased sufficiently to permit slipping the cylinder over the seal 20. After the cylinder has been slipped over the seal 20 and around the anode 11, it springs back to its original diameter to form a very close spacing between its inner surface and the outer surface of the anode.

The split cylinder 14 is entirely surrounded by a water-tight cooling jacket. This jacket comprises a water-tight cylinder 21 with an internal diameter that is larger than the external diameter of the seal 20. The cylinder 21 fits snugly over the split cylinder 14. At one end, it is secured to an annular member 22 by means of a flexible diaphragm 23. In practice, the diaphragm 23 is made of $\frac{1}{2}$ inch soft copper. The

annular member 22 is supported on the anode 11 by means of a one piece ring 24 threaded on the anode.

A gasket 26 is positioned between a split ring 27 and the ring 24 and may be compressed by means of a plurality of pivoted hooks 28. The hooks are pivoted on the head of a screw 25 as indicated by the broken lines. In order to compress the gasket 26, either the screw 25 is turned or the screw 29 is turned to lift the end of the hook away from the annular member 22.

The other end of the cylinder 21 is likewise secured to an annular member 30 by means of a flexible diaphragm 31 similar to diaphragm 23. A gasket 32 and a split ring 33 are positioned between the annular member 30 and a split ring 34. Openings 35 and 36 are provided in the annular members to provide an inlet and outlet for the cooling liquid.

20 The cooling jacket is firmly supported on the anode 11 by attaching the feet 15 thereto and wiring them on the anode.

The cooling jacket structure comprising the members 21, 22, 23, 30 and 31 is clamped on a bench with the member 30 at the bottom. The split ring 27 and gasket 26 are then placed in member 22. The anode 11, with split cylinder 14 and members 12 and 13 attached, is slipped downward to fit in the outer jacket members as shown. The gasket 26 is then compressed to form a water-tight joint.

Next, the above-described complete assembly is turned upside down and clamped on a bench with member 22 at the bottom. The split rings 33 and 34 and the gasket 32 are placed in position and the gasket 32 is compressed in the same manner as the gasket at the opposite end.

It will be noted that this structure has a decided advantage over that in which the cooling 40 jacket cylinder adjacent to the anode is supported from annular rings such as 22 and 30, because it is difficult to so mount the annular rings that the spacing between the cooling jacket cylinder and the anode is small and accurate. The flexible diaphragms 23 and 31 are provided 45 in order to prevent undesirable strains in the tube structure caused either by the unequal expansion of the anode and the water cooling cylinder during the operation of the tube or by the anode and cooling jacket getting out of alignment.

In operation, the tube is set in a vertical position and water is passed into the bottom of the cooling jacket at sufficient pressure to force the 55 water along the anode at a high velocity. The water then flows out of the cooling jacket through the annular member at the top of the jacket.

The longitudinal ribs 10 prevent eddy currents from forming in a direction lateral to the main 60 flow of the cooling liquid. At the same time, they aid the formation of eddy currents in the liquid in a direction parallel to the longitudinal axis of the tube and these eddy currents assist in cooling the anode since they move the liquid 65 from the anode surface to the cooling jacket surface.

While the ribs 10 increase the radiating surface of the anode a certain amount, their main function is to direct the flow of liquid and to 70 prevent contact between the cooling jacket and anode surface 11 as explained above.

It is important that there be a close spacing between the anode 11 and the cooling jacket 14 as, otherwise, the addition of ribs to the anode 75 will reduce the cooling effect of the liquid in

spite of the increased radiating surface. This reduction in cooling will be a result of the decreased velocity of the liquid flow at the anode surface caused by the resistance to liquid flow introduced by the ribs. If the space between anode and jacket is very small, however, the liquid in contact with the anode surface is forced to travel at approximately the same high velocity as the body of water nearer the cooling jacket.

5 In the example of my invention illustrated in 10 the drawing, the outer diameter of the anode 11 was 4.14 inches, the height of the ribs 10 was .055 inch, the length of the ribs 10 was approximately 19 inches, and the spacing between the top of the ribs 10 and the inner surface of the 15 cooling jacket 14 was .04 inch.

The spacing between adjacent ribs is sufficient to allow a flow of water that will cool the anode even though the jacket 14 comes into 20 contact with the ribs.

It may be noted that there is an advantage in putting ribs on the anode which is independent of their cooling-function. During the heat treatment process for securing a proper degree of evacuation in the tube, the anode is softened to 25 such an extent that with a smooth surface anode there is danger of the anode collapsing. The ribs strengthen the anode so that this danger of collapse is greatly reduced.

In Fig. 2 are illustrated the cathodes 47 and 30 the disk grid 44 supported on a tube 45. The specific structure of these cooperating electrodes is more fully disclosed in our copending application, Serial No. 358,608, above referred to. Practically any type of cathode and grid suitable for 35 these tubes, however, may be used, since the invention disclosed in this present application is not limited to any of these types of cathode and grid.

Various modifications may be made in our invention without departing from the spirit and 40 scope thereof, and we desire, therefore, that only such limitations shall be placed thereon as are shown by the prior art and are set forth in the 45 appended claims.

We claim as our invention:

1. A cooling system for an electron-discharge device comprising an evacuated envelope, a cylinder having longitudinal grooves which forms a portion of said envelope and which acts as an 50 electrode, another electrode cooperating therewith with a sheath surrounding said first-named cylinder, said anode being adapted to be cooled by a rapid flow of fluid between said cylinder and said sheath, the distance between the bottom of said 55 longitudinal grooves and the inner surface of the sheath being small compared with the diameter of said cylinder.

2. A cooling system for an electron-discharge device comprising in combination an evacuated 60 envelope, a cylinder having longitudinal ribs thereon, said cylinder forming a portion of said envelope and acting as an electrode, another electrode cooperating therewith, and a cylinder surrounding and spaced away from said first-named cylinder, said anode being adapted to be cooled by a rapid flow of fluid between said cylinder, said spacing between said cylinders being so close that the fluid adjacent the surface of said first cylinder moves along the longitudinal axis 65 of the tube at substantially the same velocity as the fluid adjacent the surface of said second cylinder.

3. A cooling system for an electron-discharge device comprising in combination an evacuated 70 envelope, a cylinder having longitudinal ribs thereon, said cylinder forming a portion of said envelope and acting as an electrode, another electrode cooperating therewith, and a cylinder surrounding and spaced away from said first-named cylinder, said anode being adapted to be cooled by a rapid flow of fluid between said cylinder, said spacing between said cylinders being so close that the fluid adjacent the surface of said first cylinder moves along the longitudinal axis 75 of the tube at substantially the same velocity as the fluid adjacent the surface of said second cylinder.

envelope, a cylinder having longitudinal ribs thereon, said cylinder forming a portion of said envelope and acting as an electrode, another electrode cooperating therewith, a cylinder 5 rounding and spaced away from said first-named cylinder, said anode being adapted to be cooled by a rapid flow of fluid between said cylinders, the distance between the outer surface of the first-named cylinder from which the ribs project and 10 the inner surface of the last-named cylinder being of the order of one-eighth inch and the height of said ribs being substantially one-half of the said distance.

4. A cooling system for an electron-discharge 15 device comprising in combination an evacuated envelope, a cylinder having longitudinal grooves which forms a portion of said envelope and which acts as an electrode, another electrode cooperating therewith, a sheath surrounding said first-named cylinder, said anode being adapted to be 20 cooled by a rapid flow of fluid between said cylinder and said sheath, the distance between the bottom of said longitudinal grooves and the inner surface of the sheath being of the order of one-eighth inch.

5. A cooling system for an electron-discharge 25 device comprising in combination an evacuated envelope, a cylinder which forms a portion of said envelope and which acts as an electrode, another electrode cooperating therewith, a sheath surrounding and spaced away from said first-named cylinder, means between said cylinder and sheath forming the space between said cylinder and sheath into longitudinal channels, said anode 30 being adapted to be cooled by a rapid flow of fluid between said cylinder and sheath, the distance

between the outer surface of said cylinder and the inner surface of said sheath being short compared to the diameter of said cylinder.

6. A cooling system for an electron-discharge 5 device comprising in combination an evacuated envelope, a cylinder which forms a portion of said envelope and which acts as an electrode, another electrode cooperating therewith, a sheath surrounding said first-named cylinder, means between said cylinder and sheath forming the 10 space between said cylinder and sheath into longitudinal channels, said anode being adapted to be cooled by a rapid flow of fluid between said cylinder and sheath, the distance between the outer surface of said cylinder and the inner surface of 15 said sheath being of the order of one-eighth inch.

7. A cooling system for an electron-discharge 20 device comprising in combination an evacuated envelope, a cylinder which forms a portion of said envelope and which acts as an electrode, another electrode 25 cooperating therewith, a sheath surrounding and spaced away from said first-named cylinder, a plurality of longitudinally aligned spacers disposed to insure against tangential contact between said sheath and said cylinder at either end intermediate the ends thereof, longitudinal channels intervening between said spacers, said anode being adapted to be cooled by a rapid flow of fluid between said cylinder and sheath, the distance between the 30 outer surface of said cylinder and the inner surface of said sheath being short compared to the diameter of said cylinder.

ILIA E. MOUROMTSEFF. 35
GREGORY V. RYLSKY.
